UNITED STATES PATENT OFFICE.

JACK MELTZER, OF BROOKLYN, NEW YORK.

DESIGN FOR A BOOTEE.

Application filed May 29, 1928. Serial No. 26,902. Term of patent 7 years.

To all whom it may concern:

Be it known that I, JACK MELTZER, a citizen of Mexico, residing in Brooklyn, county of Kings, and State of New York have invented a new, original, and ornamental Design for a Bootee, of which the following is a specification, reference being had to the accompanying drawing, forming part thereof.

Figure 1 is a front perspective view of the right side of a bootee showing my new design; Figure 2 is a rear perspective view of the left side of the same; and Figure 3 is a top plan view.

I claim:

The ornamental design for a bootee substantially as shown.

JACK MELTZER.
